WINDOW SASH

Henry D. Burgess, Burlingame, Calif.

Application September 23, 1946, Serial No. 698,682

1 Claim. (Cl. 189—76)

1

The invention, in general, relates to building construction and more particularly relates to an improved window sash affording substantially permanent protection against the ingress of rain, sleet, snow and dust therethrough.

The features of the present invention are entirely suitable and applicable to all types of windows including that class of windows known as casement windows whether of single or many panes and whether installed in a single sash casement or a conventional double hung sash. However, for purposes of explanation only, I have illustrated and shall hereinafter describe the invention in the environment of a single sash window having a multiplicity of panes.

A primary object of the present invention is to provide an improved window sash including means for obviating the ingress of rain, sleet, snow and undue dust and affording the ready removal of one or more panes thereof without dismantling the entire window or disturbing other panes thereof.

Another important object of the invention is to provide an improved window sash of the indicated nature which is additionally characterized by the inclusion of a continuous pane-holding and weather-strip member in at least one direction and a broken pane-holding and weather strip member in another direction for enhancing the simplicity and ease of dismantling a damaged single pane and replacement thereof.

A still further object of my invention is to provide an improved window sash of the aforementioned character which is of relatively inexpensive and simple construction.

Other objects of the invention, together with some of the advantageous features thereof, will appear from the following description of a preferred embodiment of my invention which is illustrated in the accompanying drawings. It is to be understood that I am not to be limited to the precise embodiment shown, nor to the precise arrangement of the several parts thereof, as my invention, as defined in the appended claim, can be embodied in a plurality and variety of forms.

Referring to the drawings:

Figure 1 is an elevational view of a preferred embodiment of the invention, parts being broken away to show the construction.

Figure 2 is an enlarged sectional view, taken on the line 2—2 of Figure 1.

Figure 3 is an enlarged detail of a section of the removable element of the preferred embodiment of the invention.

2

Figure 4 is an enlarged sectional detail taken on the line 4—4 of Figure 2.

Figure 5 is a fragmentary development of a portion of the preferred embodiment of the invention.

Figure 6 is a fragmentary sectional elevational view of a corner of the preferred embodiment of the invention.

Figure 7 is a perspective view of one of the removable elements of the preferred embodiment of the invention.

In its preferred form, the improved window sash of my present invention preferably comprises a pair of frames, means for detachably holding said pair of frames together, one of said pairs of frames including integral spaced continuous divisional members running in directions at substantially right angles and dividing the sash into a plurality of equal spaces which are filled with panes, and the other of said pair of frames including integral, spaced continuous members running in one direction together with broken and removable complementary elements running at right angles to the last mentioned members to divide the other of said pair of frames into similar equal spaces; said members and elements cooperatively affording pane-holding means, and weather-proof rubber strips on the edges of said members and elements, the removable disposition of said elements in said other of said pair of frames affording convenient and ready removal of one or more panes as well as replacement thereof at will.

As illustrated particularly in Figures 1, 2 and 5 of the accompanying drawings, I provide a pair of frames, designated generally by the reference numerals 11 and 12, which preferably are fabricated from a light-weight, untarnishable metal or which can be molded from a suitable plastic material or from a hard wood, as desired. The frame 11 constitutes the inner and the frame 12 the outer of my improved window sash in that frame 11 is disposed on the interior of a room in which the sash is installed while frame 12 is on the exterior of the room. The pair of frames 11 and 12 are detachably fastened together by means of a plurality of screws 13 which preferably are of the round or oval head type and the screw holes in the frame 11 are so formed as to afford counter-sinking of the screws as indicated in Figure 2 of the drawings.

In accordance with my invention, the frame 11 is so formed to an integral unit to define a bounding rim 16 consisting of integral top, bottom and side pieces in the shape of a square or rectangular

depending upon the shape of the window in which the sash is to be installed, and the improved sash of my invention includes integral, spaced members 17 and 18 spanning the rim 16 vertically and horizontally, respectively, at right angles to one another to divide the frame 11 into a plurality of equal spaces 19 to be filled with panes 20. The vertically arranged cross-members 17 of the improved sash are preferably continuous or unbroken while the horizontally arranged cross-members 18 are non-continuous or broken but welded to the sides of the rim 16 as well as to the vertically arranged members 17. Obviously, this can be reversed within the scope of the invention in that the horizontally arranged members 18 can be continuous with the vertically arranged members 17 broken and welded to the horizontally arranged members and to the top and bottom of the rim 16. The top, bottom and sides of the rim 16, as well as the members 17 and 18 are formed substantially similarly in that each of said portions of the rim as well as each of said members is provided with an integral, laterally extending tongue 21, as shown in Figures 2 and 5 of the drawings, which fit into grooves 22 of corresponding portions and elements of the exterior frame 12 of my improved sash when the two frames are fastened together. As particularly illustrated in Figure 2, the screws 13 extend through the members of frame 11 into threaded holes formed in the corresponding members and elements of frame 12.

The outer or exterior frame 12 of the preferred embodiment of the present invention generally is formed substantially similar or in the same manner as inner frame 11 in that it includes a bounding rim 26 consisting of integral top, bottom and side pieces to define a square or rectangular shape of the same dimensions as frame 11, as well as including spaced, integral continuous members 27 spanning the rim 26 vertically of the frame. However, instead of providing spaced cross-members at right angles to the members 27 which are welded thereto as in the case of frame 11, I provide a series of complementary elements 28 for frame 12 which are removably mounted thereon in that these free, complementary elements 28 are held in position on the sash when the two frames 11 and 12 are fastened together. It is clear from the annexed figures of the drawings that the arrangement of integral, vertically disposed members 27 intersected by the removably disposed horizontal cross-elements 28 affords a division of the frame 12 into a plurality of spaces 29 similar in size to the spaces 19 afforded in frame 11 by the intersecting cross-members 17 and 18 thereof. As indicated above, each of the portions of the rim 26 and of the cross-members and complementary cross-elements 27 and 28, respectively, of frame 12 is so formed as to provide the grooves 22 therein for receiving the tongues 21 formed on the corresponding portions and members of the frame 11 when the two frames are fastened together.

In Figure 6 of the accompanying drawings, I have depicted in fragmentary, sectional elevation the construction of the corners of the bounding rims 16 and 26 of the frames 11 and 12, respectively, wherein complementary, integral and continuous vertically arranged members 17a and 27a of the frames 11 and 12, respectively, fit together cooperatively to afford rigid corners of the sash when the oval or round headed screws 13a are tightened to bring the two frames together.

In accordance with my invention, all of the cooperating facing edges of the intersecting cross-members 17, 18, 27 and 28 of the frames 11 and 12 of my improved window sash, as well as the cooperating facing edges of the top, bottom and sides of the rims 16 and 26, are lined with water-proof rubber strips 31 so that when the panes 20 are installed there is not only afforded cushioned seats for the panes obviating chipping or cracking thereof but also means for preventing ingress of rain, sleet, snow, water or undue dust into the rooms having windows containing installations of my improved sash. The weather-proof rubber strips 31 are permanently affixed to the members of the frames by means of a suitable adhesive or a rubber cement.

From the foregoing, it will be apparent that one or more damaged panes can speedily, conveniently and readily be removed and replaced since it is only necessary to loosen a few screws 13 at those sections of the cross-members of the frame of the sash and lift out or remove adjacent complementary cross-elements 28 to permit withdrawal of a damaged pane. Upon substitution of a new pane, the removed complementary cross-elements 28 can be readily re-installed or re-mounted and the necessary screws 13 again tightened to bring the frames 11 and 12 of the sash together again. The removal and replacement of panes 20 is in no way detrimental to the weather-proof rubber strips 31 as there is no likelihood of ripping or damage thereto in removing the panes or replacement thereof. The improved window sash is relatively inexpensive to manufacture as the two frames 11 and 12 are substantially similar in construction and the complementary, removable cross-elements 28 are all similar for each size of sash.

I claim:

A window-sash comprising an inner frame, an outer frame, a plurality of spaced, continuous pane-holding members on said inner frame running in one direction, a plurality of spaced, non-continuous pane-holding members on said inner frame intersecting the continuous pane-holding members to divide the frame into a plurality of openings, laterally extending tongues on all of said pane-holding members, panes in said openings, a plurality of spaced, continuous pane-holding members on said outer frame running in one direction, and a plurality of spaced, non-continuous pane-holding members removably mounted on said outer frame and intersecting said plurality of spaced, continuous pane-holding members on said outer frame to divide the outer frame into a plurality of openings in alignment with the openings of said inner frame; all of said pane-holding members on said outer frame having grooves therein for receiving said lateral extending tongues on the pane-holding members of said inner frame.

HENRY D. BURGESS.
